UNITED STATES PATENT OFFICE.

GUY H. ELMORE, OF SWARTHMORE, PENNSYLVANIA.

JIG.

1,387,370.

Specification of Letters Patent.

Patented Aug. 9, 1921.

Application filed December 23, 1919. Serial No. 346,812.

To all whom it may concern:

Be it known that I, GUY H. ELMORE, a citizen of the United States, residing at Swarthmore, in the county of Delaware and 5 State of Pennsylvania, have invented certain new and useful Improvements in Jigs, of which the following is a specification.

This invention relates to jigs and particularly, though not exclusively, to jigs for 10 washing coal. The purpose of the invention is to provide a simple automatic control for the discharge of the heavier materials separated from the lighter materials in the jig, such heavier materials being, in the case of 15 coal washers, the slate and bone. The control device is of that type dependent upon the use of a float working in the jig bed. The discharge is controlled by a movable platform or leaf which retains a varying 20 mass or accumulation of the discharging heavy material against the outer side of the discharge opening from the jig. The platform is moved by the float to vary the amount of material so maintained and hence 25 to exert a varying resistance to the outflow of further material from the jig bed.

The invention is applicable to various known types of jig, but is shown applied to a type of coal washing jig now in extensive use.

Referring to the drawings:—

Figure 1 is a vertical section through the jig tank showing the piston and screen-chambers; a part of the jig tank is broken 35 away to show the slate discharge elevator;

Fig. 2 is an enlarged fragmentary view similar to a portion of Fig. 1, showing the control mechanism in a slightly different position; and

Fig. 3 is a perspective view of the discharge platform and the lever connection.

Details of the jig not essential to the invention are illustrated only generally. In the drawing 4 represents the jig tank structure. 5 is the hutch, 6 is the hutch discharge valve (here shown open) and 7 is the plunger chamber. Working in the plunger chamber 7 is the plunger 8 which is reciprocated by the eccentric 9. The 45 plunger chamber 7 communicates with the hutch 5 which extends under it and also under the screen 10. The construction of the screen 10 is not a feature of the present invention and almost any usual screen construction may be used in lieu of the offset screen shown.

The feed of material to the jig is to the space behind the partition 11. Such material flows under the partition 11 and down the inclined screen toward its discharge 60 side. The discharge side of the screen is bounded by a dam 12, over the top of which the washed coal flows. After discharge the coal passes down a dewatering screen 13. The off-flowing water is directed by the 65 plate 14 to any suitable launder. The lower edge of the dam 12 is spaced above the discharge edge of the screen 10 to leave an opening for the discharge of the slate and bone. This discharge opening preferably, 70 but not necessarily, extends the entire width of the screen 10, and its height is variable by means of a vertically adjustable gate 15 which slides in guides on the dam 12 and which may be set by handle 16 to give any 75 desired height of discharge opening up to the maximum height under the dam 12.

Hinged at 17 below the discharge edge of screen 10 and outside the opening under the adjustable gate 15 is a platform or leaf 80 18 which is approximately coextensive in length with the discharge opening. This leaf 18 is connected by a link 19 to a lever 20 fulcrumed at 21 on a bracket 22 attached to the jig tank. The link 19 passes through 85 the plate 14 and dewatering screen 13, loss of water through the plate 14 being prevented by a tube 23, connected to the upper surface of plate 14, surrounding the rod 19 and extending above the water level in the 90 jig.

The link 19 is connected to the lever on one side of the fulcrum 21, and the lever is forked at the opposite side of the fulcrum. One arm of the fork carries an adjustable 95 counter-weight 24 and the other has a pin and slot connection 25 with a rod 26 which carries a float 27 working in the jig bed. The float chosen for illustration is a disk 27 sliding freely in but filling a vertical tubular guide 28. Any other type of float may be used. The rod 26 is guided in a head 29 fixed in the upper end of the tubular guide 28. The tubular guide 28 may be supported in any suitable manner but is shown connected to the dam 12.

The pin and slot connection between the lever 20 and the rod 26 is adjustable by inserting the pin in any one of the series of holes 30 shown in the rod 26. The length 110 of the link 19 is adjustable by means of a turn-buckle 31. These two adjustments

permit the float 27 and the platform 18 to be individually adjusted with reference to the limits of motion permitted the lever 20.

Slate and bone discharged under the gate 5 15 and flowing over the platform 18 fall upon an inclined deflector plate 32 down which they slide to the chain elevator 33 which draws them out of the jig tank. This chain discharge is familiar to those skilled 10 in the art.

In the operation of the device the jig tank is kept filled with water, the eccentric 9 is rotated to reciprocate the plunger 8. The coal to be washed is fed behind the 15 partition 11. The float 27 and gate 15 and the counter-weight 24 are adjusted according to the nature of the coal to be washed, and the handle 16 is set to give the proper discharge opening. These adjustments are 20 determined by experiment and will vary somewhat according to local conditions and the preferences of the operator. Coal to be washed flows under the partition 11 and the upward pulses of water forced by the plunger 8 through the screen 10 will cause it to stratify, the coal rising to the top with layers of bone and slate beneath it. The float will automatically assume a position approximately coincident to the upper surface 25 of the bone stratum. As the strata of slate and bone become thicker the float will rise and the platform 18 will be lowered. The bone and slate retained on the platform 18 flow gradually over its free edge permitting 30 an accelerated discharge of bone and slate from the jig. When the platform 18 is raised by the fall of the float the bone and slate will accumulate in a deeper and more 35 resistant mass, thus retarding the discharge of further bone and slate. It will be noted 40 that the platform 18 will have a gradually varying retarding effect as the platform moves between its extreme positions, that it consumes no power and that it responds 45 instantly to the movements of the float.

While I have shown a disk and guide tube as the float element in this device it will be understood that I am not confined to this specific construction, but may use other 50 types of float. Various changes in the construction of the jig and in the details of arrangement of the discharge mechanism, including changes in the form of the platform, are possible and are contemplated by 55 me. For example, the same principle is applicable for the control of the discharge of metallic concentrates from jig beds, but such use will obviously require a different proportioning of the parts to suit the different type of jig. Hence I do not limit 60 myself to the structure shown.

What is claimed is:—

1. The combination with a jig having a screen and a constantly open discharge opening for heavier materials at a side of said 65

screen, of a plate over which the material after passage through said discharge opening flows; and means serving to vary the inclination of said plate to vary the rate of flow of material thereover.

2. The combination with a jig having a screen and a constantly open discharge opening for heavier materials at a side of said screen, of a plate over which the material after passage through said discharge opening flows; and automatic means, responsive to the condition of the jig bed serving to vary the inclination of said plate to vary the rate of flow of material thereover.

3. The combination with a jig having a screen and a constantly open discharge opening for heavier material at a side of said screen, of a movable support serving to maintain against the discharge side of said opening a mass of discharged material variable in amount by the movement of said support; and automatic means responsive to the condition of the jig bed and serving to move said support.

4. The combination with a jig having a screen and a constantly open discharge opening for heavier material at a side of said screen, of a float working in the bed of material on said screen; and a movable support operatively connected with said float, controlled thereby and serving to maintain against the discharge side of said discharge opening a variable mass of discharged material.

5. The combination with a jig having a screen and a discharge opening for heavier material at a side of said screen, of a float working in the bed of material on said screen; a plate hinged adjacent the edge of said screen beneath and beyond said discharge opening and serving in different angular positions to maintain different amounts of discharged material against the discharge side of said discharge opening; and operative connections between said float and plate serving upon the rise of said float to move said plate to reduce the amount of retained material.

6. The combination with a jig having a screen and a constantly open discharge opening for heavier materials at a side of said screen, of a float working in the bed of material on said screen; a support serving to maintain a mass of discharged material against the discharge side of said opening, said support being movable to vary the amount of material so maintained; connections between said float and support serving to move the support in response to changes in the position of the float, and means for adjusting said connections.

7. The combination with a jig having a screen and a discharge opening for heavier materials at a side of said screen, of a float in the bed of material on said screen; a plate

over which the material after passage through said discharge opening flows; and connections between said float and plate serving to impart to said plate different inclinations corresponding to different positions assumed by said float, the varying inclination of the plate serving to control the rate of flow of material thereover.

8. The combination with a jig having a screen and a constantly open discharge opening for the heavier materials; of a support serving to maintain an obstructive mass of discharged material against the discharge side of said opening; and means responsive

to the condition of the jig bed for varying 15 the obstructive effect of said mass.

9. The combination with a jig having a screen and a constantly open discharge opening for the heavier materials; of a support serving to maintain an obstructive mass of 20 discharged material against the discharge side of said opening, and means responsive to the condition of the jig bed serving to vary the amount of material so maintained.

In testimony whereof I have signed my 25 name to this specification.

GUY H. ELMORE.
